UNITED STATES PATENT OFFICE.

CHARLES WILLIAM AKERS, OF NASHVILLE, TENNESSEE.

MOLD FOR MAKING CONCRETE BLOCKS.

Application filed September 27, 1924. Serial No. 740,360.

To all whom it may concern:

Be it known that I, CHARLES WILLIAM AKERS, a citizen of the United States, and a resident of Nashville, in the county of Davidson and State of Tennessee, have invented certain new and useful Improvements in Molds for Making Concrete Blocks, of which the following is a specification.

This invention relates to molds for making concrete blocks and has for its object the provision of a device which is simple in construction and adjustable for making blocks of different sizes.

A further object of the invention is the provision of a block making machine having movable side plates for exposing the form block and a locking device for rigidly securing the sides in position.

A further object of the invention is the provision of a mold having a wooden pallet and hinged side members and a division plate located centrally between the side plates whereby several blocks may be formed in a single mold.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a side view of a mold constructed according to the principles of my invention.

Figure 2 is an end view of the same.

Figure 3 is a vertical transverse section of the device.

Figure 4 is a plan view of a modified form of mold for forming hollow blocks.

Figure 5 is a view in perspective of the hinged end member of the mold.

Figure 6 is a view in perspective of a core adapted to be applied to the mold for making rectangular blocks in order to form hollow blocks.

Referring more particularly to the drawings, 1 designates a table supported by legs 2. The table has a pair of pallets 3 and 4 extending centrally and longitudinally of

said table and spaced from each other to receive a division plate 5. This division plate is secured in position by angle irons 6 that extend vertically between the pallets 3 and 4 and terminate in a plane which passes through the upper edges of the side plates 7 and 8 of the mold. The angle irons 6 are secured to transverse brace bars 9 which form part of the table construction.

Each of the side plates 7 and 8 are hinged to an adjustable plate 10 as shown at 10^a. The adjustable plates are provided with slots 11 as shown in Figure 4 through which is inserted a bolt 12. The bolts are secured in the table 1 and the plates are held in their adjusted position by means of wing nuts 13 having a threaded engagement with the bolts 12.

Each of the side plates are limited in their hinged movement by means of bars 14 rigidly connected at their upper ends to the side plates 7 and 8. As shown in Figure 3 the lower ends of the bars are spaced from the adjusting plates 10 and are bent outwardly from the side plates so that when said side plates are tilted outwardly the free ends of the bars 14 will engage the adjustment plate and limit the swinging movement of the side plates. An end plate 15 has an internal flange 16 bent outwardly and a straight portion abutting the end of side plate 8. A hinge 18 secured to the flange 16 connects the end plate to one end of the side plate 7. A lug 19 is rigidly connected with the portion 17 of the end plate 15 and upon which is pivotally connected the bifurcated end 20 of an arcuately shaped link 21. The other end of the link is also bifurcated as shown at 22 and in which is pivotally connected a cam 23 having an operating handle 24.

Upon the side plate 8 is mounted a curved lug 25 which is adapted to be engaged by the cam 23 when the lever 24 is moved to the position shown in Figure 4 and is adapted to lock the end plate 15 to the adjacent ends of the side plates 7 and 8. The end plate 15 is provided with a pair of vertically disposed indentations 26 adapted to receive the concrete mixture 27 and form V-shaped ribs upon the outer end of the concrete block. The opposite ends of the side plates 7 and 8 are closed by means of an end plate 28 having in-bent ribs 29 projecting into the molds and adapted to form 110

V-shaped grooves 31 in one end of the blocks 27 which are adapted to fit the V-shaped ribs 30 at the opposite ends of alined blocks. The end plate 28 is pivotally connected as 5 shown at 32 to one end of the side plate 7 and is also provided with a lug 19 having an arcuately shaped link 21 carrying at its other end the cam member 23 and an operating arm 24.

10 The adjusting plates 10 are slidably mounted on spaced cleats 33, the cleats being secured to the table 1. Angle irons 34 are secured in spaced relation to the side plates 7 and 8 for reinforcing the same, the 15 lower pair of reinforcing angle irons 34 being located adjacent the hinges.

The molding device just described is for the purpose of forming rectangular molds. In order to form concrete blocks of the hollow type I apply cores generally designated by the numeral 36 to the opposite inner faces of the side plates 7 and 8. These cores consist of a piece of sheet metal having a back 37 which is bent around at its 25 ends as shown at 38 and bent inwardly to form attaching flanges 39. These flanges are perforated as are the side plates 7 and 8 and rivets passing through the alined perforations are adapted to secure the flanges 39 and likewise the core 36 to the side plates. Strips of metal 40 cut to conform to the contour of the edges of the plate 37 are secured in any approved manner to the opposite side edges of the plate 37 and prevent 30 the concrete mixture from falling in between the side plates 7 and 8 and the bottom 37 of the core 36.

The end plates 15 and 28 are provided with vertical machined grooves 42 adapted 40 to receive the ends of the division plate 5 for aiding in maintaining the division plate in its proper relation within the mold.

Whether it is intended to form solid or hollow blocks the side plates 7 and 8 are 45 placed in position, that is vertically, and the end plates are swung on their hinges 32 until their flanges 17 abut the projecting ends 43 of the reinforcing angle irons 34. The links 21 are swung into a position where 50 the cam member 23 will engage the curved lug 25 and the operating arms 24 are moved inwardly and the end plates are therefore locked to the side plate 8. The concrete mixture which is of the dry type is packed 55 or tamped in the mold and the smooth straight edges of the side plates 7 and 8 permit the excess concrete to be readily scraped from the green blocks forming said mold. When the process of forming the block is 60 complete the arms 24 are again swung outwardly, that is towards the links 21 and the cams 23 are released from the curved lugs 25 so that the side plates may move outwardly swinging on the hinges 10^a and be 65 limited in their movement by the lower end

of the bar 14 engaging the adjusting plates 10.

The pallets 3 and 4 are merely placed upon the transverse bars 9 of the table so that the pallets of larger size may be placed 70 therein and the adjusting plates 10 moved outwardly after the wing nuts 12 have been released. Due to the different spacing of the side plates 7 and 8 the wider end plates 15 and 28 replace the former end plates. 75 It may be only necessary to remove the pins from the hinges 18 and 32 and shove the section of the leaf of the hinge on the larger end plate into position whence the pins may be returned and complete the hinges. 80

The blocks which are produced with the use of the cores 36 are formed with grooves at their sides when they are employed in building constructions and properly associated. The adjacent side walls of the 85 blocks form voids. While the blocks in themselves are what we may term solid blocks, yet when properly associated produce in effect a hollow block building construction. 90

What I claim is:

1. A concrete mold comprising adjusting plates, side plates hingedly connected with the adjusting plates, means for adjustably spacing the adjustable plates and side plates, end plates hingedly connected to one side plate, and means for releasably locking the opposite ends of the end plates to the other side plate. 95

2. A concrete mold comprising adjusting plates, side plates hingedly connected with the adjusting plates, means for adjustably spacing the adjustable plates and side plates, end plates hingedly connected to one side plate, means for releasably locking the 100 opposite ends of the end plates to the other side plate, and a division plate mounted in a fixed position and located centrally of the side plates. 105

3. A concrete mold comprising adjusting plates, side plates hingedly connected with the adjusting plates, means for adjustably spacing the adjustable plates and side plates, end plates hingedly connected to one side plate, means for releasably locking the 110 opposite ends of the end plates to the other side plate, and means for limiting the outward movement of the hinged side plates. 115

4. A concrete mold comprising adjusting plates, side plates hingedly connected with the adjusting plates, means for adjustably spacing the adjustable plates and side plates, end plates hingedly connected to one side plate, means for releasably locking the 120 opposite ends of the end plates to the other side plate, and cores adapted to be secured to the side plate for forming hollow concrete blocks. 125

CHARLES WILLIAM AKERS,
